UNITED STATES PATENT OFFICE.

FRED T. LOBBEY, OF WINSLOW, INDIANA, ASSIGNOR TO SULLIVAN MACHINERY COMPANY, A CORPORATION OF MASSACHUSETTS.

MINING MACHINE.

Application filed May 18, 1918, Serial No. 235,384. Renewed December 11, 1924.

To all whom it may concern:

Be it known that I, FRED T. LOBBEY, a citizen of the United States, residing at Winslow, in the county of Pike and State 5 of Indiana, have invented certain new and useful Improvements in Mining Machines, of which the following is a full, clear, and exact specification.

My invention relates to mining machines. 10 My invention has for its object to provide improved means whereby a mining machine may be controlled in an improved manner. A further object of my invention is to provide improved means whereby a 15 room and pillar machine may be fed relative to the face in an improved manner during a cutting operation preparatory to the transverse cutting operation, and thereafter moved transversely as desired. A still further object of my invention is to provide 20 improved means whereby a mining machine, and especially, though not necessarily, one of the type utilizing a continuous flexible feeding member, may be angled in an improved manner, as for example when moving 25 from its sumping to its transverse cutting position or during any later operation, with increased facility and without any undue strain upon the machine. These and 30 other objects and advantages of my improved construction will, however, herein after more fully appear.

In the accompanying drawings I have shown for purposes of illustration one embodiment which my invention may assume in practice.

In these drawings,—

Fig. 1 is a diagrammatic view of a mining machine equipped with my improvement 40 and disposed in its position after completion of its sumping cut and with the parts connected to begin the transverse cut.

Fig. 2 is a similar diagrammatic view showing the machine in the first stages of 45 its transitional movement from its sumping position to its position during the transverse cut.

Fig. 3 is a similar diagrammatic view showing the machine in the position occupied 50 after the completion of its transitional movement and when ready to make its transverse cut.

Fig. 4 is a similar diagrammatic view showing the machine after the completion

of its transverse cut and when ready to be 55 withdrawn from the face.

In this illustrative construction, I have shown my invention as applied to use in connection with a standard type of room and pillar mining machine including a 60 frame 1 and a forwardly projecting cutter bar 2 having a cutter chain 3 rotatable around the same by power transmitted in any well known manner from a suitable motor 4 carried on the frame. As usual, it 65 will be noted that this machine is also provided at the rear end of its frame with an upstanding feed driving or operating member 5, preferably likewise driven from the motor in a well known manner in opposite 70 directions at different predetermined speeds, and a plurality of adjacent rotary guiding members 6, 7, and 8, cooperating with the member 5 in a well known manner, as well as another rotary guiding member 9 located 75 adjacent the front end of the frame, each of these members 6, 7, 8, and 9 being adapted to guide a continuous flexible feeding member 10 cooperating with the driving member 5. As this member 10 is herein 80 shown in the form of a feed chain, each of the members 5, 6, 7, 8, and 9 is also shown herein as of sprocket form. In the use of a standard machine such as described when undercutting a room or the like from right 85 to left, for example, the advance end of the flexible feeding member 10 is connected to a jack 11 fixed at the left hand rib, while the chain 10 is extended back therefrom 90 along the face, around the sheave 9, rearward along the machine frame, around the sheave 6, around the driving sprocket 5, and around the sheave 7, the other end of the chain being connected to a fixed point 95 at the receding side of the machine and usually at the opposite or right hand rib.

In my improved construction, I have provided improved means adapted to be utilized with various types of machines other than that described, but herein shown, for 100 purposes of illustration, as applied to that type, which means comprise a double strand connection connectible between a fixed point at the right hand rib and the rear end of the machine whereby that end of the machine, 105 as distinguished from being maintained substantially stationary when angling, as for example in preparing for the transverse cut,

is enabled to move relative to and away from the rib but at a slower rate than the free end of the cutter bar, so that, while the desired direct turning movement is obtained, all deleterious straining of the feeding mechanism is avoided. Referring more particularly to the drawings, it will be noted that in my improved construction, I have provided a preferably horizontally disposed guiding member or sprocket 12 at the receding side of the machine, i. e. the right hand rib, the same being shown herein as carried in a suitable support 13 fixed in the rib, although obviously any other well known means of mounting the member 12 may be used if desired. Around this member 12 it will be noted that the right hand end of the flexible feeding member 10 is passed after it has passed off of the rear guiding member 7, and then directed back toward the machine frame. It will also be observed that I have attached to this end of the chain 10 a hook 14 adapted to be removably connected at will in a suitable cooperating hook or eye 15 carried on the right hand side of the machine frame 1 and at a point closely adjacent the rear end thereof.

As a result of this improved construction, it will be observed that, after the insertion of the sumping cut and the connection of the parts as shown in Fig. 1, when the feed driving member 5 is started in operation upon the feeding member 10, by a clockwise rotation at a predetermined slow or cutting speed the machine is swung about its rear end as a pivot at the same time that its rear end is moved away from the rib. More specifically, it will be observed that the receding portion of the flexible feeding means is lengthened at approximately one-half the speed that the advancing portion thereof is drawn in, and that, as a result, the rear end of the machine is thus moved away from the rib at approximately one-third the speed of movement of the outer end of the bar, so that, as distinguished from a previous construction wherein the rear end of the machine is maintained stationary, all deleterious strain is removed at the same time that the desired direct turning movement and its consequent saving in time, etc. is obtained. Through the use of my improved construction, it will also be observed that after the machine has completed its turning movement, the same may obviously be fed across the face in the usual manner by simply disconnecting the hook 14 from the cooperating member 15 and catching the hook over one of the links of the chain, substantially as shown in Fig. 3, thereby forming the usual single strand connection. It will also be evident that whenever it is thereafter desired to vary the angle of the machine relative to the face, as when cutting out an obstruction or when angling

at the left hand rib, this may be very readily accomplished by simply adjusting the position of the hook upon the chain and thereby varying the turning effect obtainable through varying the effective length of the rearwardly located lead of the latter. Moreover, it will be evident that when the rotation of the feed operating member 5 is reversed, as is usual in machines of the character shown, and the same is driven at its predetermined high speed in a counter-clockwise direction, the receding portion of the flexible feeding means may not only be drawn in at the predetermined high speed usually used to move the machine over the bottom, but that by reason of my improved construction making possible selective utilization of the double strand receding portion, the machine may also be moved relative to the receding portion at a predetermined speed faster than the slow feed and approximately half as fast as the fast feed, but in the same direction as the latter.

It will be noted that through the use of my improved mechanism, herein including the double strand connection extending from the rear of the machine to a fixed point and returned and connected to the frame, it is possible to vary the rate of feeding movement of the machine irrespective of any possible change in rate of movement of the feed operating member on the machine and thereby provide further possible variations in speed of feed without in any way interfering with the function and operation of the feed operating member or in any way interfering with the entire practicability of the mechanism as a single strand mechanism during the transverse cut. Further, it will be noted that through the use of my improved construction with a machine of the single continuous feed member type, it is made possible to eliminate entirely the necessity for a take-up mechanism located on the machine or adjacent one of the ribs, such a machine through my improvement being adapted to be prepared for the transverse cut without necessity for the provision of such a take-up member. Referring to the particular construction shown, by the use of my improved construction, it will be observed that it is possible to obtain the desired direct turning effect without placing a severe strain on the machine, the double strand connection, which herein extends to the rear end of the machine, acting to turn the machine effectually as desired and at the same time to reduce the machine strains. Attention is also directed to the fact that, through the use of my improvement, it is possible for an operator to connect the parts very readily and quickly without moving from his usual post, it only being necessary for him to connect up the hook with the ma-

chine when preparing to begin the swinging movement, and to disconnect the same and drop it over the chain in order to obtain the single strand connection desired during the 5 transverse cut. As indicated above, through the adjustment of the hook along the chain it is also evident that the angular position 10 of the machine relative to the face may be very readily adjusted at any time. These 15 and other advantages of my improved construction will, however, be clearly apparent to those skilled in the art.

While I have in this application specifically described one embodiment which my 15 invention may assume in practice, it will be understood that this form is used for illustrative purposes only and that the invention may be modified and embodied in various other forms without departing from its 20 spirit or the scope of the appended claims.

What I claim as new and desire to secure by Letters Patent is:

1. A mining apparatus comprising a frame having a cutter bar extending longitudinally 25 thereof, flexible transverse feeding means therefor including single strand advance and receding portions at opposite ends of said frame, and means whereby said receding portion may be operatively connected at 30 will as a double strand connection.

2. A mining apparatus comprising a frame having a cutter bar extending longitudinally thereof, flexible transverse feeding means therefor including single strand advance 55 and receding portions at opposite ends of said frame, and means whereby said receding portion may be used as a double strand connection in a cutting operation preparatory to the transverse cut.

40 3. A mining apparatus comprising a frame having a cutter bar extending longitudinally thereof, flexible feeding means adapted to act on the opposite ends of said frame including a single strand advance portion and 45 a receding portion, and means whereby said receding portion may be operatively connected in single or double strand connections and have its effective length varied at a predetermined speed or at a predetermined 50 fraction of said speed.

4. A mining apparatus comprising a frame having a cutter bar extending longitudinally thereof, flexible feeding means adapted to act on the opposite ends of said frame including a single strand advance portion and 55 a receding portion, and means whereby said receding portion may be operatively connected in single or double strand connections and have its effective length varied at a predetermined fast speed or at a predetermined 60 fraction of said speed.

5. A mining apparatus comprising a frame having a cutter bar extending longitudinally thereof, flexible feeding means adapted to 65 act on the opposite ends thereof including

advance and receding portions and a feed operating member, and means whereby while said feed operating member rotates in the same direction said receding portion may be operatively connected in a single or a double 70 strand connection and have its effective length varied at a constant speed or at a predetermined fraction of said speed.

6. In a mining machine, a frame having a projecting cutter bar extending longitudinally thereof, flexible transverse feeding means therefor including a flexible feeding member extending from adjacent the rear end of said frame, and means for selectively connecting said member to said frame in a 80 single or double strand connection.

7. In a mining machine, a frame having a projecting cutter bar extending longitudinally thereof, flexible transverse feeding means therefor including a flexible feeding member extending from adjacent the rear end of the receding side of said frame, and means for selectively connecting said member to said frame in a single or a double 85 strand connection.

8. A mining apparatus comprising a frame having a cutter bar extending longitudinally thereof, flexible transverse feeding means adapted to act on the opposite ends of said frame including a single strand advance portion and a receding portion, and means for operatively connecting the receding portion to said frame in a double strand connection during cutting preparatory to the transverse cut and thereafter in a single 100 strand connection.

9. A mining apparatus comprising a frame having a cutter bar extending longitudinally thereof, flexible transverse feeding means adapted to act on the opposite ends of said frame including a flexible advance portion, a flexible receding portion extending from adjacent the rear end of said frame, and a reversible feed operating member acting on the latter, and means for selectively operatively connecting said portion as a single or double strand connection.

10. In a mining machine, a frame having a projecting cutter bar, feeding means therefor including a flexible feeding member extending from one side of said frame, and means for selectively connecting said frame to the rib in a single or double strand connection of said flexible member.

11. In a mining machine, a frame having a forwardly projecting cutter bar, feeding means therefor including a flexible feeding member extending from one end of said frame to the rib and back to said frame, and means for at will rendering said flexible feeding member effective as a single strand connection.

12. In a mining machine, a frame having a forwardly projecting cutter bar, feeding means therefor including a continuous flexi-

- ble member extending laterally in opposite directions from the opposite ends of said frame, and means for selectively connecting said frame to the rib in a single or double strand connection of said flexible member.
13. In a mining machine, a frame having a forwardly projecting cutter bar, feeding means therefor including a continuous flexible feeding member extending laterally in opposite directions from the opposite ends of said frame, and means for selectively connecting the rear end of said frame to the rib in a single or double strand connection of said flexible member.
14. In a mining machine, a frame having a forwardly projecting cutter bar, feeding mechanism therefor including a continuous flexible feeding member extending laterally therefrom in opposite directions, and means for selectively connecting one end of said frame to the rib in a single or a double strand connection, one of said connections being of adjustable length.
15. In a mining machine, a frame having a forwardly projecting cutter bar, feeding means therefor including a flexible double strand connection extending from the rear end of said frame to the rib and back to the rear end of said frame, and means for selectively connecting the rear end of said frame to the rib in said double strand connection or in a single strand connection.
16. In a mining machine, a frame having a forwardly projecting cutter bar, flexible feeding means therefor including a double strand connection extending from the rear end of said frame to the rib and back to the rear end of said frame, and means for selectively connecting the end of said connection to the rear end of said frame as aforesaid or to itself.
17. In a mining machine, a frame having a forwardly projecting cutter bar, power driven feeding mechanism therefor including a double strand connection extending from the rear end of said frame to the rib and back to the rear end of said frame, and means selectively connectible with the frame as aforesaid, or stationary with respect to the rib for controlling the angle of said bar.
18. In a mining machine, a frame having a forwardly projecting cutter bar, power driven feeding mechanism therefor including a double strand connection extending from the rear end of said frame to the rib and back to the rear end of said frame, a guiding member for said connection disposed between the strands thereof, and means connectible at will to retard movement of the rear end of said frame or to arrest movement of one of the strands of said connection relative to the rib.
19. In a mining machine, a frame having a forwardly projecting cutter bar, power

driven feeding mechanism therefor including a double strand connection extending from the rear end of said frame to the rib and back to the rear end of said frame, a guiding roller for said connection disposed between the strands thereof at a point adjacent one of the ribs, and means for selectively connecting the end of said connection to the rear end of said frame in a double strand connection as aforesaid or to the rib in a single strand connection.

20. In a mining machine, a frame having a forwardly projecting cutter bar, feeding mechanism therefor including a flexible feeding member extending to points at opposite sides of the frame, the advance end of the same being fixed, a guiding member disposed at the receding side of said frame around which the other end of said member is extended and directed back to said frame, and means for connecting the end of said flexible member with the rear end of said frame.

21. In a mining machine, a frame having a forwardly projecting cutter bar, feeding mechanism therefor including a flexible feeding member extending to points on opposite sides of the frame, the advance end of the same being fixed, a guiding member disposed at the receding side of said frame around which the rear end of said member is extended and directed back to said frame, and means for connecting the end of said flexible member with the rear end of said frame including a hook carried on one of said elements.

22. In a mining machine, a frame having a forwardly projecting cutter bar, feeding mechanism therefor including a flexible feeding member extending to points at opposite sides of the frame, the advance end of the same being fixed, a guiding member disposed at the receding side of said frame around which the other end of said member is extended and directed back to said frame, and means for connecting the end of said flexible member with the rear end of said frame including a hook carried on said end of said member.

23. In a mining machine, a frame having a forwardly projecting cutter bar, feeding mechanism therefor including a flexible feeding member extending to points at opposite sides of the frame, the advance end of the same being fixed, a guiding member disposed at the receding side of said frame around which the other end of said member is extended and directed back to said frame, and means for successively connecting the end of said flexible member with the rear end of said frame or to itself at a point intermediate its ends including a hook carried on said end of said member.

24. In a mining machine, a frame having a forwardly projecting cutter bar, feeding

- mechanism therefor including a flexible feeding member extending to points on opposite sides of the frame, the advance end of the same being fixed, a guiding member disposed at the receding side of said frame around which the other end of said member is extended and directed back to said frame, and means for connecting the end of said flexible member with the rear end of said frame including a hook carried on said end of said member and a cooperating hook receiving member on said frame.
25. In a mining machine, a frame having a projecting cutter bar, feeding means therefor comprising a flexible connection extending between the front end of said frame and a fixed point adjacent the face, a flexible connection extending from the rear of said frame and parallel to the face to a fixed member disposed in spaced relation to said frame at the receding side thereof, means for varying the length of said second mentioned connection comprising a rotatable member operative to shorten or lengthen said connection at a rate proportional to the rate of rotation thereof, and means whereby the effective length of said connection may be varied at different constant rates and for the full length thereof if desired without variation in the rate of rotation of said rotatable member.
